UNITED STATES PATENT OFFICE.

VERNON CANO, ARTHUR A. CANO, AND LEWIS CANO, OF NEW YORK, N. Y.

ELECTRICAL-CIRCUIT CONTROLLER.

1,103,657.

Specification of Letters Patent.

Patented July 14, 1914.

Application filed November 28, 1913. Serial No. 803,578.

To all whom it may concern:

Be it known that we, VERNON CANO, ARTHUR A. CANO, and LEWIS CANO, citizens of the United States, and residents of New

5 York, in the county of New York and State of New York, have invented certain new and useful Improvements in Electrical-Circuit Controllers, of which the following is a specification.

10 This invention relates to electrical circuit-controllers and especially to a multiple circuit-controller by means of which two normally separated electrical conductors may be brought into contact at any one of a 15 plurality of points.

A special object is to furnish a multiple circuit-controller of the simplest and cheapest construction for closing contact between two adjacent conductors at any one or more 20 of a large number of points, the preferred construction employed being one in which substantially nothing more is involved than the two conductors themselves and a supporting strip for carrying them.

25 The invention is adapted for use in connection with any ordinary electrical controlling or other circuit in which it is desired to make contact at will between two main conductors at any one or more of a 30 large number of points in the length of said conductors, the invention being especially applicable to the giving of a visual or audible signal from various points in a building or room and to the protection of walls, etc., 35 against burglarious entry.

Other features of the invention not hereinbefore referred to will be hereinafter described and claimed and are illustrated in the accompanying drawings, in which—

40 Figure 1 is a face view of an electrical circuit-controller embodying our invention and comprising two electrical conductors carried and normally separated by a strip of insulating material; Fig. 2 is a similar view 45 showing a modification of the construction; Fig. 3 is a view similar to Fig. 1 showing the application of the invention in a circuit-controller of large area having several rows of points of contact of conductors instead of

the single row shown in the other views, and 50 Fig. 4 is an enlarged transverse section of Fig. 1, the section being taken in line 4—4, Fig. 1.

Similar characters designate like parts in all the figures of the drawings. 55

Referring first to Fig. 1, we have illustrated in this view a pair of electrical conductors carried by an insulating support or strip in such a manner that said conductors are normally separated from each other at 60 one or more points. Said insulating support also embodies in this case means for bringing said conductors into contact with each other at any one of said points. While this view illustrates a circuit-controller with conductors having a plurality of points of separation and a plurality of devices for effecting contact of the conductors at such points, the invention is embodied in a single unit of the controller shown in said view and such a 70 unit would comprise two conductors such as are illustrated at 2 and 3, normally separated at a single point, as indicated clearly in Fig. 4, and a device, such as the tongue 4, integral with the main body or strip of insulating material, 5, for pressing said conductors into electrical contact. The strip 5 shown is in the preferred construction a flexible strip of insulating fiber relatively thin but of sufficient thickness to have a fair amount of 80 stiffness, and this strip has a large opening or openings, such as 6, therein at opposite sides of which the conductors 2 and 3 cross each other but are out of contact normally. This contact may be made in any suitable 85 manner, but we prefer, as just stated, to employ tongues, such as 4, which are disposed in the openings 6 but are of smaller area, so as to leave a clear space around them except at the point of connection of each tongue 90 with the strip 5, the object of this being to facilitate the insertion of the conductor 3 in place under each tongue and between it and the body of the strip.

Each conductor may be secured to the 95 strip in any desired manner, but preferably by threading it through openings properly located in the strip. The conductor 3 is

here shown as a flat strip of sheet metal and the conductor 2 as an ordinary round wire. For the round wire conductor small circular holes, such as 7, are preferably provided; 5 while for the flat strip, long slots, such as 8, are preferable, these being disposed in pairs close together as shown in Fig. 1. The flat strip is threaded through these slots and under the tongues 4 and always passes the 10 openings 6 on one side thereof, that is, at the front, as seen in Fig. 1; while the conductor or wire 2 is threaded through the small round holes 7 in such a manner that it always crosses an opening 6 and the conductor 3 at 15 the opposite side of the strip 5, that is, at the back thereof. Thus at the points of crossing the conductors are always normally separated so that the circuit remains open and no current can pass. The tongue 4 is 20 located at one side, here the front, of both of the conductors and of the device as a whole and is intended to close contact between the conductors by pressing them together. To accomplish this each tongue of 25 course has sufficient movement to assure the bringing of the conductors into engagement, and the conductors themselves have sufficient play in the openings 7 and 8 and are sufficiently loose to permit them, though 30 normally separated, to be brought together readily.

It will be noticed that the conductor 3 extends substantially in a straight line from end to end of the circuit-controlling strip, 35 whereas the conductor 2 is passed back and forth transversely of the conductor 3 for a considerable portion of its length, in order that points of crossing may be established at each opening by each conductor at which 40 electrical contact may be made. The conductors 2 and 3 at their ends may be suitably secured to terminals, such as the metallic eyelets 9 and 10, which complete the circuit-controlling strip. This strip as a 45 whole may then be secured in place along any wall or other surface to which it is desired to apply it and may be connected in any proper electrical circuit to be controlled by merely connecting the terminals of said 50 circuit to one pair of terminals 9 and 10 on the strip.

Fig. 2 illustrates a modification in which the conductor 2, the tongues 4, the strip 5, the large openings 6, the small round openings 7 for receiving the conductor 2 and the 55 contact terminals 9 and 10 are or may be identical with those shown in Fig. 1. In this view, however, instead of threading a flat electrical conducting strip under the 60 tongues 4 and through long slots, an ordinary round wire, 3', is threaded under said tongues and through small round openings, 8', similar to those shown at 7. Otherwise the construction is substantially identical

with that of Fig. 1 and the operation the 65 same.

In Fig. 3 we have illustrated a modification of the invention showing its application to the protection of a surface of large area. Here a conductor 2 is threaded back and 70 forth across and lengthwise of a relatively wide sheet, 5', of insulating material and passes through numerous small openings 7 disposed in a plurality of rows both lengthwise and crosswise of said sheet. We have 75 also shown three flat strip conductors, 3, like those of Fig. 1, these three conductors being illustrated as parallel with one another and as connected at their opposite ends by conducting wires, 11, by which they 80 are joined in multiple to the terminals 10 as before; the conductor 2 being connected substantially as before described to the contact terminals 9. The contact strips 3 are threaded, as in Fig. 1, through pairs of parallel slots 8. The construction is such that there are three rows of breaks at the openings 6 and the tongues 4 at any one of which points the circuit may be closed by pressing on the proper tongue. For convenience the 85 large openings 6 and the tongues in alternating rows in this view are staggered, as are the pairs of slots 8. The positions of some of the small openings 7 for the round wire 2 are also varied because of the staggering of the tongues of different rows. In other respects, however, the construction is 90 substantially identical with that of Fig. 1 and the mode of operation is the same, there being, however, instead of a single series of 95 breaks in multiple three series of breaks in multiple.

It will be obvious from the foregoing that our improved electrical circuit-controller may be employed either as a single unit or 105 as a strip consisting of a single row of units, or that it may embody a large number of elements in each of a large number of rows for protecting a surface of great area over which contact may be established when any 110 one of a large number of tongues, such as 4, is pressed either accidentally or intentionally.

We claim—

1. An electrical circuit-controller, comprising a strip of insulating material having a relatively large opening, a pair of normally-separated conductors secured to said strip and crossing each other at said opening and one being movable to and from a position for contact with the other, and means at one side of said conductors for pressing them together.

2. An electrical circuit-controller, comprising a strip of insulating material having a relatively large opening, a pair of normally-separated conductors secured to said strip and crossing each other at oppo-

- site sides of said opening and one being movable to and from a position for contact with the other, and means at one side of said conductors for pressing them together.
5. 3. An electrical circuit-controller, comprising a strip of insulating material having a relatively large opening, a pair of normally-separated conductors secured to said strip and crossing each other at opposite sides of said opening, and a tongue on said strip at one side of said conductors for pressing them together.
10. 4. An electrical circuit-controller, comprising a strip of insulating material having a tongue outlined by a cut portion of the strip, and a pair of normally-separated conductors secured to said strip and crossing each other at one side of said tongue and at opposite sides of the opening formed by the tongue and adapted to be brought into contact by pressure on the opposite side of said tongue.
15. 5. An electrical circuit-controller, comprising a strip of insulating material having a tongue outlined by a cut portion of the strip, a pair of normally-separated conductors secured to said strip and crossing each other at one side of said tongue and at opposite sides of the opening formed by the tongue and adapted to be brought into contact by pressure on the opposite side of said tongue, and circuit terminals on said strip to which said conductors are connected.
20. 6. An electrical circuit-controller, comprising a flexible strip of insulating fiber having a tongue outlined by a cut portion of the strip, and a pair of normally-separated conductors secured to said strip and crossing each other at one side of said tongue and at opposite sides of the opening formed by the tongue and adapted to be brought into contact by pressure on the opposite side of said tongue.
25. 7. A multiple-contact electrical circuit-controller, comprising a strip of material having a row of relatively large openings therein, a pair of normally-separated conductors secured to said strip and crossing each other at opposite sides of said openings and one being movable to and from a position for contact with the other, and means at each opening for pressing said conductors together.
30. 8. A multiple-contact electrical circuit-controller, comprising a strip of material having a row of relatively large openings therein, a pair of normally-separated conductors secured to said strip and crossing each other at opposite sides of said openings, and tongues on said strip at each opening for pressing said conductors together.
35. 9. A multiple-contact electrical circuit-controller, comprising a strip of material having a row of tongues each outlined by a cut portion of the strip, and a pair of normally-separated conductors secured to said strip and one of which crosses the other at one side of each tongue and is adapted to be brought into contact with the other by pressure on the opposite side of said tongue.
40. 10. A multiple-contact electrical circuit-controller, comprising a strip of material having a row of tongues each outlined by a cut portion of the strip, and a pair of normally-separated conductors secured to said strip and one of which extends substantially in a straight line lengthwise of the strip and the other of which crosses the first at one side of each tongue and is adapted to be brought into contact with the first by pressure on the opposite side of said tongue.
45. 11. A multiple-contact electrical circuit-controller, comprising a strip of material having a row of integral tongues each formed in an opening of larger area, and a pair of normally-separated conductors secured to said strip, one of which conductors extends substantially in a straight line lengthwise of the strip under said tongues and the other of which crosses the first at one side of each tongue and is adapted to be brought into contact with the first by pressure on the opposite side of said tongue.
50. 12. A multiple-contact electrical circuit-controller, comprising a strip of material having a row of relatively large openings therein, a pair of normally-separated conductors secured to said strip and crossing each other at opposite sides of said openings, two series of openings in said strip through which said tongues are threaded to locate them in position, and means at each of said large openings for pressing said conductors together.
55. 13. A multiple-contact electrical circuit-controller, comprising a strip of material having a row of tongues each outlined by a cut portion of the strip, a pair of normally-separated conductors secured to said strip and one of which crosses the other at one side of each tongue and is adapted to be brought into contact with the other by pressure on the opposite side of said tongue, and two series of openings in said strip through which said conductors are threaded to locate them in position.
60. 14. A multiple-contact electrical circuit-controller, comprising a sheet of material having a plurality of rows of relatively large openings therein, a pair of normally-separated conductors secured to said sheet and crossing each other at opposite sides of the openings of all of said rows, and means at each opening for pressing said conductors together.
65. 15. A multiple-contact electrical circuit-controller, comprising a sheet of material having a plurality of parallel rows of tongues

each outlined by a cut portion of the sheet, and a pair of normally-separated conductors secured to said sheet and one of which crosses the other at one side of each tongue in each row and is adapted to be brought into contact with the other conductor by pressure on the opposite side of said tongue.

Signed at New York, in the county of

New York, and State of New York, this 11th day of Nov., A. D. 1913.
